UNITED STATES PATENT OFFICE

GUY F. WETZEL, OF CHICAGO, ILLINOIS

DESIGN FOR A SHELF RACK

Application filed April 20, 1931. Serial No. 39,564. Term of patent 3½ years.

To all whom it may concern:

Be it known that I, GUY F. WETZEL, a citizen of the United States, residing at Chicago, in the county of Cook and State of Illinois, have invented a new, original, and ornamental Design for a Shelf Rack, of which the following is a specification, reference being had to the accompanying drawings, forming a part thereof.

Of the drawings, Fig. 1 is a plan view of the shelf rack, showing my new design; and Fig. 2 is an elevation of the same.

I claim:

The ornamental design for a shelf rack as shown.

GUY F. WETZEL.
